SEWING MACHINE ATTACHMENT

Wallace E. Kline, Perryville, Mo., assignor to
The Puritan Manufacturing Company, Bos-
ton, Mass., a company of Massachusetts

Application October 19, 1942, Serial No. 462,642

10 Claims.

(Cl. 112—62)

This invention relates to sewing machines, particularly of the type and kind used in stitching heavy materials, for example, in the stitching of soles of shoes. More particularly, the invention relates to an attachment for machines of this type and kind in the form of a workpiece supporting plate and feed member disposed beneath the presser foot of the machine to facilitate free and easy guiding of the workpiece through the machine, while at the same time, insure firm support of the workpiece in proper position beneath the needle or stitching mechanism of the machine.

The novel features of the invention will be best understood from the following descriptions when taken together with the accompanying drawing, in which certain embodiments of the invention are disclosed, and in which the separate parts are designated by suitable reference characters in each of the views; and in which:

Fig. 1 is a side elevation view of an attachment, partly in section.

Fig. 2 is a front elevation view.

Fig. 3 is a plan view of the structure as seen at Fig. 2.

In sewing machines of the kind under consideration, it has been the common practice to employ fixed workpiece supporting plates beneath the presser foot and needle mechanism of the machine, and particularly, in the operation of stitching the soles of shoes where difficulty has been experienced in feeding or guiding the workpiece through the machine.

It is the purpose of my invention to eliminate these objectionable features by providing a plate attachment, comprising an angularly disposed workpiece supporting surface having an irregular surface, preferably in the form of longitudinal teeth thereon and to dispose within an apertured or recessed portion of this plate a conical roughened surface wheel or roller, freely rotatable on an axis, arranged centrally beneath the plate and on the support for the plate. This bevelled and corrugated or tooth like roller is arranged to engage the workpiece where the stitching operation is performed thereon to permit free movement of the workpiece over the supporting plate, while at the same time maintaining in conjunction with said plate an angularity to the workpiece which will facilitate the stitching operation and at the same time to firmly support the workpiece in position during the stitching operation.

In the accompanying drawing, I have illus-

trated one adaptation of the invention and in Figs. 1 and 2, 10 represents a supporting bar, the lower end of which is recessed, as seen at 11 and apertured as seen at 12 for mounting the bar in connection with a sewing machine. The apertures 12, being elongated to properly centralize the attachment with respect to the needle 13 of the sewing machine.

In Fig. 1 of the drawing, 14 represents a presser foot, the lower hook or foot end 15 of which is provided with the usual elongated aperture 16, through which the needle 13 operates.

Secured to the upper end of the bar 10 is a workpiece supporting plate 17, held in position on the bar by two screws 18. The end portion 19 of this plate which is arranged on the bar is flat, whereas the workpiece supporting end 20 is offset or angularly disposed in a downward direction. This end being curved slightly to form a lip as seen at 21. The upper surface of the angular workpiece supporting end has longitudinal teeth or projections 22 to firmly engage a workpiece in retaining the same against shifting thereon particularly, during the stitching operation. These teeth or corrugations, however, do not interfere with the movement or feed of the workpiece through the machine.

The central portion of the plate has a large aperture or cutout 23, substantially of the form illustrated in Fig. 3 of the drawing. The dove tailed end 24 of this aperture being adapted to freely receive a workpiece supporting wheel or roller 25, whereas the other end of the aperture has an offset portion 26 to provide clearance for the needle operation of the machine.

The roller 25 is mounted on a screw or stud 27, secured to the upper end of the bar 10 and retained against displacement therefrom by a set screw 28, having a lock nut 29. The slotted head 30 of the screw or stud supports the conical or bevelled roller against displacement from the bar, and this stud forms an axis upon which the roller is freely rotatable. In other words, sufficient clearance is provided in the mounting of the stud to provide a free rotation of the roller upon its axis.

The bevelled surface of the roller is provided with circumferentially spaced ribs 31, which in turn are formed into teeth or projections by circumferential grooves 32, and these teeth or projections will engage the workpiece and by reason

of the free rotary movement of the roller the workpiece is freely fed through the machine in the stitching operation.

In Fig. 1 of the drawing, I have diagrammatically illustrated, in section, a part of the sole 33 of a shoe, part of an upper 34 in the operation of stitching the upper to the sole as indicated at 35. By reason of the angular support of the workpiece by the end portion 20 of the plate 17, as well as angularity provided by the roller 25. The workpiece is supported in a position which facilitates the stitching operation as at 35, allowing the presser foot end 15 to snugly fit along the irregular contour of the upper of a shoe during the stitching operation. The teeth 22 of the supporting plate, as well as the teeth of the roller retains the workpiece at all times in proper position, and the portion 36 of the roller which projects above the surface of the plate engages the workpiece to slightly lift the same from the plate in the feeding operation thereof.

It may be said that the workpiece support comprises a unit presenting one bevelled or angular surface, and this surface is divided into a stationary or non-movable portion and a movable portion, the latter being the surface of the roller. In considering Figs. 2 and 3 of the drawing, it will appear that the surface of this workpiece supporting unit disposed beneath the stitching mechanism is for the most part occupied by the surface of the roller, as this surface is materially wider than the narrow portion 37, note Fig. 3.

Having fully described my invention, what I claim as new and desire to secure by Letters Patent is:

1. The combination with a sewing machine of a workpiece supporting attachment, said attachment comprising a plate having a downwardly inclined surface arranged beneath the needle of the machine, said surface being formed by elongated tooth like projections extending in the direction of the feed of a workpiece beneath the needle of the machine, means exposed through said surface engaging a workpiece to aid in the operation of stitching the same, and said last named means comprising a freely rotatable element.

2. The combination with a sewing machine of a workpiece supporting attachment, said attachment comprising a plate having a downwardly inclined surface arranged beneath the needle of the machine, said surface being formed by elongated tooth like projections extending in the direction of the feed of a workpiece beneath the needle of the machine, means exposed through said surface engaging a workpiece to aid in the operation of stitching the same, said last named means comprising a freely rotatable element, and said element having a bevelled surface conforming to the inclination of the inclined surface of said supporting plate.

3. A workpiece supporting attachment for stitching machines, said attachment comprising a post, an axis arranged at right angles to one end portion of the post, a roller freely rotatable on said axis, said roller having a bevelled surface adapted to be engaged by the workpiece and arranged substantially in alignment with the stitching mechanism of the machine at one side of the needle of the machine, stationary means secured to said post adjacent and partially enveloping said roller forming a support for the workpiece, and said means having an upper surface conforming in part to the bevelled surface of said roller.

4. A workpiece supporting attachment for stitching machines, said attachment comprising a post, an axis arranged at right angles to one end portion of the post, a roller freely rotatable on said axis, said roller having a bevelled surface adapted to be engaged by the workpiece and arranged substantially in alignment with the stitching mechanism of the machine at one side of the needle of the machine, stationary means on said post adjacent and partially enveloping said roller forming a support for the workpiece, the bevelled surface of said roller having teeth or projections, and said last named means having a surface substantially paralleling the bevelled surface of the roller.

5. A workpiece supporting attachment for stitching machines, said attachment comprising a post, an axis arranged at right angles to one end portion of the post, a roller freely rotatable on said axis, said roller having a bevelled surface adapted to be engaged by the workpiece and arranged substantially in alignment with the stitching mechanism of the machine at one side of the needle of the machine, means on said post adjacent said roller forming a support for the workpiece, the bevelled surface of said roller having teeth or projections, said last named means having a surface substantially paralleling the bevelled surface of the roller, and said last named surface being formed by elongated teeth arranged at right angles to the axis of said roller.

6. A workpiece support attachment for sewing machines comprising a plate, means adjustably supporting the plate beneath the needle of the machine, said plate having a horizontally flat portion, and a downwardly inclined curved portion arranged beneath the needle of the machine, the lower end of said inclined curved portion terminating in an inwardly turned lip, and the outer surface of said inclined portion being formed by longitudinally extending and transversely spaced ribs.

7. A workpiece supporting attachment for stitching machines, said attachment comprising a mounting portion and a work engaging plate inclined downwardly with respect thereto and arranged beneath the needle of the machine, means for adjustably supporting the attachment in the machine to position said plate with respect to the needle and presser foot of the machine, the central portion of said plate being apertured, and a roller mounted for free rotation in the aperture of said plate, with the surface of said roller exposed through the plate to engage the workpiece, in providing free movement of the workpiece over the plate in the operation of stitching the same.

8. A workpiece supporting attachment for stitching machines, said attachment comprising a mounting portion and a work engaging plate inclined downwardly with respect thereto and arranged beneath the needle of the machine, means for adjustably supporting the attachment in the machine to position said plate with respect to the needle and presser foot of the machine, the central portion of said plate being apertured, a roller mounted for free rotation in the aperture of said plate, with the surface of said roller exposed through the plate to engage the workpiece, in providing free movement of the workpiece over the plate in the operation of stitching the same, and said roller being conical in form presenting a bevelled surface in alignment with the angular portion of said plate.

9. A workpiece supporting attachment for stitching machines, said attachment comprising

a mounting portion and a work engaging plate inclined downwardly with respect thereto and arranged beneath the needle of the machine, means for adjustably supporting the attachment in the machine to position said plate with respect to the needle and presser foot of the machine, the central portion of said plate being apertured, a roller mounted for free rotation in the aperture of said plate, with the surface of said roller exposed through the plate to engage the workpiece, in providing free movement of the workpiece over the plate in the operation of stitching the same, said roller being conical in form presenting a bevelled surface in alignment with the angular portion of said plate, part of said roller projecting above the mounting portion of said attachment, and the upper surface

of said plate having longitudinally extending teeth arranged at right angles to the axis of rotation of said roller.

10. The combination with the needle and presser foot mechanism of a stitching machine, of a workpiece support, said support comprising a stationary plate having an attaching portion and a downwardly inclined apertured work engaging portion arranged beneath the needle of the machine, and a freely rotatable substantially conical member arranged in the aperture of said downwardly inclined portion in presenting in alignment with the surface of said portion a bevelled surface over which a workpiece is free to pass.

WALLACE E. KLINE.
